UNITED STATES PATENT OFFICE

JOHN P. LYNN, OF CHICAGO, ILLINOIS, ASSIGNOR TO DUR-O-LITE PENCIL CO., OF CHICAGO, ILLINOIS, A CORPORATION OF ILLINOIS

PENCIL

Application filed August 24, 1928. Serial No. 301,718.

This invention which relates generally to mechanical pencils, or other implements of similar character, is concerned primarily with certain improvements in the construction of the bodies therefor, particularly such as are produced from a material that is moulded to shape under heat and pressure. With a body that is moulded in a two-part die difficulty is frequently encountered in 10 fusing or otherwise uniting the complementary body sections whether they be produced individually or in biscuits. The losses resulting from imperfect union may amount to considerable in commercial practice. The aim of this invention is to provide a means which assists in joining the complementary sections of such a body and which in case of little or no bond resulting from incomplete fusion will nevertheless provide 15 a mechanical union permitting the unrestricted use of the body the same as though its parts were joined by a perfect union.

A suggestive embodiment of my invention is set forth in the accompanying drawing 20 wherein—

Figure 1 is a longitudinal section through a mechanical pencil of conventional construction, a portion of the body thereof being shown in elevation;

25 Figs. 2 and 3 are enlarged transverse sections therethrough taken respectively on lines 2—2 and 3—3 of Fig. 1;

Fig. 4 is an end elevation of the body lining per se; and

30 Fig. 5 is a side elevation thereof.

The pencil herein illustrated by way of example comprises a body A having, if desired, at its upper end a ferrule 6, in which is held an eraser 7 protected by a cap 8 which is fitted thereon. Fitted to the lower 35 pencil end is a cone-shaped tip B having a rotatable connection therewith.

The pencil body is shown as provided with an axial opening 9 having one or more slots 40 therein for the accommodation of a head 10 which is carried on a threaded plunger 11. At its lower end the passage 9 opens into a round chamber 12 of enlarged diameter wherein is fitted a lining 14 which receives engagement 45 from a tube 13 extending upwardly from the

tip B. The walls of this tube are frictionally engaged with the lining of the chamber 12 so as to establish a rotatable connection between the tip and pencil body. Extending axially within the tip is a guide tube and such other parts as are needful to cooperate with the plunger 11 to effect propulsion through the tip of an active lead C.

55 A pencil body which is produced by a moulding process may comprise two complementary halves *x* and *y* (see Fig. 2) which, if perfectly constructed, are fused together along their longitudinal meeting surfaces *z*. The occasional imperfect joining of the body sections renders desirable a supplemental 60 connection and this is provided mechanically according to my invention. For this purpose, I utilize the lining 14 at one point and optionally elsewhere another lining 15 of 65 similar form. In the construction shown, 70 this latter lining is fitted within a chamber extending axially of the body from its upper end for a distance sufficient to provide a magazine for reserve leads. The two linings, as shown, occupy positions at opposite ends of 75 the pencil body, but this is not a point of consequence in the present invention.

75 Each lining is in the form of a sleeve having a plurality of parallel slots 16 cut into its walls from one end thereof. In producing 80 these slots the displaced material which is in the form of narrow strips is rolled or curled back, preferably into the form of eyes 17 which are disposed adjacent the inner ends of the slots and upon the outer face of the lining. Linings of this character are carried by the mandrels which occupy positions between the die moulds when the fusible material is heated and pressed therebetween in the process of producing the bodies. This material 85 is caused to flow through the slots 16 and eyes 17 so as to become interlocked therewith irrespective of any union resulting from fusion between the two body sections. Because of the axial positions of the linings and the projection of its eyes into the several body sections, a mechanical interconnection is assured such that separation thereof is positively prevented. The losses attendant upon the 90 commercial manufacture of bodies in which 95 100

such interlocking linings are employed are reduced to less than one per cent. Such linings are also advantageous in that they reinforce the body walls throughout their thinnest portions, and in the case of the lining at the lower body end, a more accurate and uniform surface is presented to the tube 13 which engages frictionally and rotatably therewith.

My invention is susceptible of use with many forms of moulded bodies comprising 10 two or more complementary sections which in the fusing operation are joined physically, and by reason of the supplementary mechanical interconnection which is provided a 15 stronger and more durable product is assured.

I claim:

1. A moulded body for pencils and the like formed of longitudinally complementary physically joined sections between 20 which is an axial opening, and a lining within the opening having slotted walls and having projecting means embedded within the several sections to effect a mechanical union therebetween, substantially as described.

2. A moulded body for pencils and the like formed of a plurality of sections and having a longitudinal opening, said sections being joined along longitudinal planes, and having means extending from one section 30 to the next adjacent section and permanently secured to both sections for bonding said sections together.

3. A moulded body for pencils and the like formed of a plurality of sections and having a longitudinal opening, said sections being fused along longitudinal planes, and having means extending from one section to the next adjacent section and permanently secured to both sections for bonding said sections together.

4. A moulded body for pencils and the like formed of a plurality of sections and having a longitudinal opening, said sections being joined along longitudinal planes, and a lining for said opening having means thereon for engaging said sections to hold them assembled.

5. A moulded body for pencils and the like formed of a plurality of sections and having a longitudinal opening, said sections being joined along longitudinal planes, and a lining for said opening having outwardly struck portions for engaging said sections to hold them assembled.

6. A moulded body for pencils and the like formed of a plurality of sections and having a longitudinal opening, said sections being joined along longitudinal planes, and a lining for said opening having outwardly struck portions forming eyes for engaging said sections to hold them assembled.

7. A moulded body for pencils and the like formed of a plurality of sections and having a longitudinal opening, said sections being joined along longitudinal planes, and a tubu-

lar metal lining having a plurality of longitudinal slots formed in one end thereof, some of the metal removed to form said slots being bent outwardly to form eyes which are adapted to engage said sections to hold them assembled.

8. A reinforcing member for use in pencils and the like comprising a metal tube having a plurality of longitudinal slots formed in one end thereof, some of the metal displaced to form said slot being bent outwardly to form eyes.

9. A reinforcing member for use in pencils and the like comprising a metal tube having a plurality of eyes struck outwardly therefrom.

In testimony whereof, I have hereunto set my hand this 22 day of August, 1928.

JOHN P. LYNN.
